By his Attorney:

Inventor:
Samuel Toomey,

J. S. Brown.

UNITED STATES PATENT OFFICE.

SAMUEL TOOMEY, OF CANAL DOVER, OHIO.

VEHICLE-AXLE.

SPECIFICATION forming part of Letters Patent No. 367,076, dated July 26, 1887.

Application filed May 14, 1887. Serial No. 238,197. (No model.)

To all whom it may concern:

Be it known that I, SAMUEL TOOMEY, a citizen of the United States, residing in Canal Dover, in the county of Tuscarawas and State 5 of Ohio, have invented an Improved Axle for Sulkies and other Vehicles; and I do hereby declare that the following is a full and exact description of the same, reference being had to the accompanying drawings, making part of 10 this specification.

This invention belongs to the class of curved or bent axles, and particularly to bent axles made of wood, or having a wooden stock with metallic spindles or axle arms or journals. 15 The essential defect in bent wooden axles, otherwise desirable, heretofore has arisen from the want of strength and stiffness in the bent or curved portions, the grain of the wood having become partially ruptured and considerably 20 weakened by the bending, so that it is difficult to keep the axle in true shape.

My invention consists in making the wooden axle or stock substantially straight in the middle portion, with the bends or curves near the 25 ends thereof, and in forming extensions of the spindles or axle-journals to serve as braces by extending as chords across from one extremity of the curved portion to the other.

In the drawings, Figure 1 represents a side 30 view of one of my improved axles complete; Fig. 2, an under side view of the same; Fig. 3, a side view of one of the combined spindles and braces employed, shown separately; Fig. 4, a transverse section of the axle in a plane indicated by the line x x , Fig. 1.

The wooden axle or stock A has the middle portion thereof straight, or substantially so, and this portion, not being weakened in shaping, is made with sufficient strength and stiffness 40 without any addition thereto. The two ends are curved as much as required to raise the axle to the desired height, the extreme ends

being preferably recurved upward slightly to give the proper direction to the terminations.

The steel or iron axle journals or arms B B 45 have extensions C C, which serve as braces, extending from the ends of the wooden axle straight across, obliquely upward, to the inner ends of the curved portions, substantially as shown in Fig. 1. A portion, c, of each brace 50 extension next to the spindle proper is curved to properly conform to the shape of the extremities of the wooden axle, and this portion of the braces is sunk into grooves cut in the under side of the wooden axle, substantially 55 as shown. This portion of the braces is best secured to the wooden axle by clips E E, surrounding both and coupling the spindles to the axle. The inner end of each brace is also preferably held by a clip, G, to the wooden 60 axle. The extremity of the brace may also be bolted or screwed to the under side of the axle.

I claim as my invention—

1. In combination with a bent wooden axle curved near the two ends, metallic spindles or 65 axle-journals having brace extensions reaching from one end to the other of the curved portions of the axle, substantially as and for the purpose herein specified.

2. The combination, with a bent wooden 70 axle, A, curved near the ends, of spindles or journals B B, having brace extensions C C reaching from end to end of the curved portions, and a portion of each extension sunk into grooves in the under side of the axle, sub- 75 substantially as and for the purpose herein specified.

In witness whereof I have hereunto signed my name in the presence of two subscribing witnesses.

SAMUEL TOOMEY.
